UNITED STATES PATENT OFFICE.

CHARLES W. CHENEY, OF BOSTON, MASSACHUSETTS.

CLYSTERIZING APPARATUS.

Application filed August 13, 1927. Serial No. 212,793.

This invention pertains to proctotherapy and more particularly to clysterizing apparatus. In accordance with certain systems of diagnosis and treatment now practiced it is necessary to employ clysterizing apparatus designed to permit withdrawal of the irrigating fluid used in effecting the evacuation together with the contents of the colon through the clyster or enema tube,—employing suction or vacuum to effect the desired result.

Apparatus of the above class frequently comprises elevated receptacles adapted to hold enema, antiseptic, or bacterial culture solutions, etc., and these receptacles communicate by means of pipes of proper length and diameter with the colon tube and the delivery or suction tube, one or more valves being provided for controlling the flow of the various fluids.

In order to obtain the desired pressure, the fluid receptacle is elevated to a considerable height and there is thus a long run of pipe between each fluid receptacle and the colon tube. When the controlling valve is opened, the air entrapped in the connecting pipe as well as in any intermediate valve connections or fittings is forced into the colon tube ahead of the fluid. In certain systems of treatment a long colon tube is used which is adapted to reach as far as the cæcum, and the irritation produced by such a long colon tube often causes marked peristaltic action of the colon which may become quite violent when the irrigating fluid is discharged from the end of the tube. In certain pathological conditions of the colon, the colonic canal becomes very much constricted at points, as for example by abnormally sharp flexures of the colon, accretions upon its inner wall, the abnormal pressure of other organs, etc. and when the colon tube is passed through such a constricted portion, little if any of the normal passage remains unfilled. When the relatively large body of air in the pipes and connections is now expelled into the upper colon it is unable to escape through the clogged or constricted canal and under these conditions the violent peristaltic action often causes extreme pain to the patient. At times the spasmodic constriction of the colon which results from the above conditions may become so prolonged and powerful as to collapse the colon tube and even to prevent its

immediate withdrawal, and thus the patient is obliged to remain in great pain until relaxation of the colon from muscular fatigue permits withdrawal of the irrigating fluid and tube.

In accordance with my present invention I provide means for venting air or gas from the colon tube during the introduction of the latter and from the pipe connections when the fluid begins to flow toward the colon, and I thus avoid a former cause of discomfort and danger in the use of such apparatus.

In the accompanying drawings I have illustrated one form of my venting means, by way of example, as embodied in a novel and simple clysterizing apparatus which itself comprises several desirable features hereinafter pointed out, but my new venting means is applicable to clysterizing apparatus of other types and is not restricted to use in the specific apparatus here illustrated.

In the drawings:

Fig. 1 is a side elevation, partly in section and partly broken away, illustrating more or less diagrammatically my improved form of clysterizing apparatus, having embodied therein my improved venting means;

Fig. 2 is a side elevation, to larger scale, partly in section, showing a connector device employed in the apparatus of Fig. 1, and

Figs. 3 and 4 are side elevations, to smaller scale, showing connector devices of modified construction.

The numeral 1 designates a suitable support of any desired kind, such for example as a shelf attached to the wall or carried by adjustable means for varying its height, or an elevated table or stand top. This support, of whatever nature, is preferably provided with a plurality of openings according to the number of fluid receptacles to be used. In these openings are set the receptacles 2, 3, 4 etc. for holding fluid of the desired character, for example a saline or alkaline irrigating or enema fluid, an antiseptic solution, a solution of bacterial culture, or in fact any desired liquid to be employed in the treatment.

My improved apparatus preferably comprises a manifold or header 5, preferably of elongate tubular form and having spaced controlling valves 6 and 7 adjacent to its opposite ends. This header 5 is also pro-

vided, in the space between the valves 6 and 7, with a plurality of valved nipples 8, 9 and 10 corresponding in number to the fluid receptacles. Pipes 11, 12 and 13 lead from the bottoms of the receptacles 2, 3 and 4 to the valved nipples 8, 9 and 10 respectively for conveying the contents of the respective receptacles to the header or manifold 5.

One end 14 of the header 5 is adapted to receive a suction or delivery tube 15 which extends to any suitable point of delivery, such for example as the receptacle 16 or a drain. The opposite end 17 of the header 5 receives a tube 18 which is secured to one branch 19 of a T-connection 20. Preferably this T-connection 20 is transparent, being made for example of glass, and the branch 21 of this T-connection which is in alignment with the branch 19 receives one end 20 of a colon tube. This colon tube is flexible and terminates in a rounded, conical end 23 provided with one or more delivery openings 24 and 25. This type of tube is well known in the surgical or allied arts and forms no part of my present invention. Such a tube is illustrated for example in the Stohlman Patent No. 340,739, April 27, 1886 in connection with a stomach pump.

The upright branch 26 of the T-connection 20 receives the lower end of a vent tube 27. This tube is normally open and unobstructed and leads upwardly to a point 28 which is preferably as high as the top of the highest one of the fluid receptacles, or at least as high as the maximum fluid level in such receptacle. This vent tube may be supported in any suitable manner and may be rigid or flexible as preferred.

Preferably the T-connection comprises an enlargement 30 providing an air separating chamber with which the bores of the several branches 19, 21 and 26 communicate. If the T-connections be of glass, this enlargement may be made by blowing a bulb of suitable size integral with the branches, but whether of glass or other material, the enlargement may, if desired, consist of an independent receptacle of any suitable material or size to which the branches are suitably attached. As shown in Figs. 1 and 2, this enlargement is of bulbous or spherical form, but in Fig. 3 I have shown the T-connection as having an enlargement 30^a of generally conical form; while in Fig. 4 I have shown the T-connection as devoid of such enlargement. While as shown in Fig. 4 the connecting member may be without the enlargement, I prefer to provide a chamber of relatively large capacity at the junction of the several branches of the T-connection, since such a chamber tends to break up the continuity of the fluid flow and helps to separate any air in the form of bubbles entrained in the fluid, thus permitting such air to rise freely through the vent tube 27.

In the operation of the device, the several receptacles are provided with the desired fluids, the valves 6, 7, 8, 9 and 10 being closed and the pipe 15 extending to a suitable receptacle or drain. The colon tube 22 is now inserted to a distance depending upon the type of treatment to be employed and during such insertion entrapped air or gas may freely escape through the open vent 27, although at this time the several valves 6, 7, 8, 9 and 10 are closed.

The valve 6 is now opened and one of the valves 8, 9 or 10 is also opened to permit the fluid from the corresponding receptacle to pass into the header 5, and thence into the colon tube. Upon opening such valve 8, 9 or 10, the air entrapped in the corresponding pipe 11, 12 and 13, as well as in the header 5, is forced forwardly and escapes through the vent tube 27, so that it is not driven into the colon tube, while the chamber within the enlargement 30 breaks up the continuity of the flow of fluid so that any air entrapped in the latter is separated and may escape through the vent. The treatment is now carried out in the usual manner by manipulation of the valves 8, 9 and 10 and the valves 6 and 7, and during the treatment the freely open tube 27 constitutes what may be termed a safety valve to prevent undue rise of pressure in the system, thus safeguarding the patient from injury or discomfort.

Whenever the colon tube is to be drained, the vent tube 27 may be closed by means of a valve 29, or otherwise, so that it will not interfere with the desired suction through the header 5 and the colon tube 2. By making the T-connection 20 transparent it is possible to observe the condition of the fluid passing through the system, and thus to determine the progress of the treatment and the completion of the drainage of the colon and colon tube.

While I have herein illustrated one desirable arrangement of parts, I wish it to be understood that the invention is not to be limited by the specific illustration of apparatus herein shown, but that various changes in arrangement of parts may be made without departing from the spirit of the invention.

I claim:

1. Clysterizing apparatus comprising an elevated receptacle for fluid, a T-connection having a central portion providing a relatively large air separating chamber and branches having relatively small bores leading from said chamber, a conduit leading from the receptacle to one branch of the T-connection, a colon tube communicating with another branch of the T-connection, and a vent tube attached to the third branch of the T-connection and leading upwardly therefrom.

2. Clysterizing apparatus comprising a

plurality of elevated fluid receptacles, an elongate tubular header provided with a pair of spaced valves, a pipe leading from each receptacle to a point in the header intermediate said valves, a valve for each pipe, a T-connection having one branch connected to one end of the header, a colon tube con-

nected to another branch of the T-connection, and air vent means connected to the third branch of the T-connection. ¹⁰

Signed by me at Boston, Massachusetts, this 12th day of August, 1927.

CHARLES W. CHENEY.
